James Garrett

ATTORNEY

UNITED STATES PATENT OFFICE.

JAMES BARRETT, OF NEW YORK, N. Y.

SHAVING KIT.

1,343,703.

Specification of Letters Patent. Patented June 15, 1920.

Application filed November 11, 1918. Serial No. 262,020.

To all whom it may concern:

Be it known that I, JAMES BARRETT, a citizen of the United States, and resident of the borough of Manhattan, city, county, and 5 State of New York, have invented certain new and useful Improvements in Shaving Kits, of which the following is a specification.

The present invention relates to improvements in shaving kits, and is an improvement over the shaving kit disclosed in my co-pending application Serial No. 209,040, filed December 27, 1917, an object of the invention being to provide such a device in 15 which shaving water may be conveniently and quickly heated, and in such manner as not to melt or otherwise deteriorate the shaving soap. I also propose to provide a holder for the soap to the end that the same 20 may be more conveniently fitted in the kit, and also propose to provide improved means for supporting the fuel. A further object is to provide an improved form of mirror and cover construction peculiarly suited to the 25 present arrangement, the mirror being of such construction that it may be readily removed for cleaning, and during heating so that it will not tarnish or be otherwise affected by the heat or moisture.

30 With these and other objects in view embodiments of my invention are shown in the accompanying drawings, and these embodiments will be hereinafter more fully described with reference thereto and the invention will be finally pointed out in the 35 claims.

In the accompanying drawings:

Figure 1 is a front elevation of an embodiment of my invention showing the top 40 and mirror raised.

Fig. 2 is a vertical sectional view thereof.

Fig. 3 is a plan view of the same.

Fig. 4 is a horizontal sectional view taken along the line 4—4 of Fig. 1 and showing 45 the door open and the fuel container removed from the heating compartment.

Fig. 5 is a similar view to Fig. 4 and showing a modified form of fuel support, the same being shown in full lines within the 50 heating compartment and in dotted lines removed therefrom.

Fig. 6 is a vertical sectional view of the removable soap container.

Fig. 7 is a vertical sectional view of the 55 device with the cover closed and the soap container removed; this view as also Fig. 6

being turned 90° from the sectional view shown in Fig. 2.

Fig. 8 is an enlarged detailed sectional view of either the water or the air vent conduit; and

Fig. 9 is a transverse sectional view taken along the line 9—9 of Fig. 8.

Similar reference characters indicate corresponding parts throughout the several 65 figures of the drawings.

Referring to the drawings and more particularly to Figs. 1 to 4 thereof, the embodiment of my invention shown therein comprises a cylindrical casing 10, having intermediate its ends a water compartment adapted to contain the water A, and comprising an upper wall 12, a lower wall 13 and a cylindrical side wall 14 soldered or otherwise suitably secured to the inner surface of the casing 10. This compartment may, if desired, be formed by merely providing spaced horizontal partitions secured at their edges to the casing, the casing itself forming a side wall of the compartment. 70

A relatively large upper compartment 15 is provided above the water compartment, while a relatively large lower compartment 16 is provided below the same, the said lower compartment being closed at its end by 85 means of a removable base 17, the rim 18 of which is adapted to frictionally engage the outer surface of the casing, this frictional engagement being sufficient to hold the base in place. This base may, if desired, be permanently secured.

The open end of the upper compartment is adapted to be closed by means of a cover 19 having a rim 20, and provided with a projecting lug 21, hingedly mounted in a 95 bracket 22 provided upon the casing and adapted to be fixed in its position by means of a bolt 23 and a knurled nut 24, which upon being tightened frictionally binds the two embracing portions 22^a and 22^b of the 100 bracket upon the lug 21. Thus the cover may be tightly secured over the end of the compartment 15 as shown in Fig. 7, and in dotted lines in Fig. 2, or it may be fixed at any desired angle in its open position. 105

Within the cavity of the cover there is disposed a mirror 25, preferably metallic, provided centrally with a screw threaded stem 26 projecting through an aperture 27 of the cover and having threaded thereon a 110 knurled nut 28, which serves the double purpose of removably securing the mirror in

place and as a knob for manipulating the cover.

A pair of diametrically opposite upstanding tubes 29 and 30 are provided in the upper wall 12 of the water compartment, being spaced from the wall of the casing and terminating substantially below the upper edge thereof. These tubes are identical in form and either one may serve as a water transference conduit or an air vent conduit upon tipping the kit.

Within the upper compartment 15 there is adapted to be placed a soap container consisting of a lower cup portion 31 having at its upper edge a laterally extending flange 32, and a rim 33 extending upwardly therefrom, and in which there is secured by soldering a confining upstanding wall 34, slightly flared so that the upper end snugly fits the interior of the casing 10 when the soap container is placed in the compartment 15.

A pair of tubes 35 and 36 are inserted in the portion 31 of the soap container at diametrically opposite points and these inclose the tubes 29 and 30 when the soap container is inserted, washers 37 and 38 being provided surrounding the tubes and upon which the soap container rests. The soap B is packed in the container, which is of such dimensions as to accommodate the usual sized cake.

A lip 39 is provided at the upper edge of the wall 34 and extends substantially half way around the same. This lip may be used for removing surplus lather from the shaving brush, and also upon tilting the kit to transfer the water from the water compartment to the soap compartment it confines the water to said soap compartment, preventing spilling.

The tubes 29 and 30 are both interiorly threaded and are adapted to receive screw closure caps 40 and 41, the enlarged heads 40^a and 40^b of which project over the ends of the tubes 35 and 36 thereby securing the soap container in the compartment.

The lower or heating compartment 16 is provided with an opening 42 over which there is disposed a door 43 provided with a knob 44 and mounted upon a hinge 45, a spring 46 coiled about the said hinge yieldingly holding the door over the opening. Upon the inner side of the door there is pivotally mounted upon a bracket 47 a lazy tongs arm or support 48 to the ends of which there is secured a ring 49 in which rests a fuel containing pan 50. By opening the door this pan is withdrawn from the compartment as shown in Fig. 4, and the fuel, preferably a small piece of solidified alcohol C, is placed therein. This is lighted, and upon closing the door, is disposed beneath the water compartment. The lazy

tongs support permits accurate positioning of the fuel pan. A plurality of openings 51 are provided in the heating compartment portion of the wall of the casing, these openings being arranged in two rows above and below the level of the pan and serve to supply air to the compartment to support combustion.

In Fig. 5 I have illustrated a modified form of fuel support comprising a rigid arm 52 projecting inwardly from the inner side of the door and having a fuel pan 53 secured at the end thereof.

During the heating the caps 40 and 41 are removed to allow the escape of steam, and preferably the soap container is removed as shown in Figs. 6 and 7. In order to prevent the heat from affecting the mirror this may also be removed, and if the cover is closed the steam will be allowed to escape through the aperture 27 in the cover.

My improved shaving kit may be used conveniently by any shaver, the water being heated rapidly, and where hot water is not available it will prove particularly useful. It will be especially valuable to soldiers, campers and in arid regions where water is scarce, as it is capable of containing enough water to last for a considerable period. It is compact and will take up very little room.

I have illustrated and described preferred and satisfactory embodiments of my invention but it is obvious that changes may be made therein within the spirit and scope thereof as defined in the appended claims.

I claim:

1. A shaving kit comprising a water compartment, and another compartment above it, a water conduit connected to said water compartment and leading therefrom to said upper compartment, a soap container disposed in said upper compartment adapted to be removed therefrom, a body of soap filling the lower portion thereof, said container having a passage adapted to embrace said water conduit, said water conduit terminating above said body of soap and below the upper end of said upper compartment, said water conduit adapted to transmit water from said water compartment to the upper surface of said body of soap upon tilting the said kit.

2. A shaving kit comprising a water compartment and another compartment above it, a water conduit connected to said water compartment, an air vent conduit connected to said water compartment, said water conduit and air vent conduit leading to said upper compartment, a soap container disposed in said upper compartment adapted to be removed therefrom, means provided in said soap container having passages therethrough adapted to receive said water conduit and said air conduit, and closure means

for said conduits adapted to engage said means of said soap container to secure said soap container in said upper compartment.

3. A shaving kit comprising a water compartment, and another compartment above it, a water conduit connected to said water compartment and leading therefrom to said upper compartment, a soap container disposed in said upper compartment and adapted to be removed therefrom, a body of soap filling the lower portion thereof, said container having a passage adapted to embrace said water conduit, said water conduit ter-
- 5
- 10

minating above said body of soap and below the upper end of said upper compartment, 15 said water conduit being adapted to transmit water from said water compartment to the upper surface of said body of soap upon tilting said kit, and said soap container having at its upper edge an inwardly projecting 20 lip which is adapted to serve as a lather scraper for the shaving brush and as a guard to prevent spilling of the water during said tilting.

JAMES BARRETT.
